UNITED STATES PATENT OFFICE.

WILLIAM M. TULLEY, OF PORTSMOUTH, OHIO.

REGISTER-OPERATING MEANS.

Original application filed October 27, 1921, Serial No. 510,744. Divided and this application filed July 6, 1922. Serial No. 573,123.

To all whom it may concern:

Be it known that I, WILLIAM M. TULLEY, a citizen of the United States, residing at Portsmouth, in the county of Scioto and State of Ohio, have invented certain new and useful Improvements in Register-Operating Means; and I do declare the following to be a full, clear, and exact description of the invention, such as will enable others skilled in the art to which it appertains to make and use the same.

This application is a division of my co-pending United States application Serial No. 510,744, filed October 27, 1921, and patented April 10, 1923, Patent No. 1,451,240, the present case being devoted to operating means for the register.

Registers are often provided with a pivotally mounted operating arm to which an operating rod or the like is connected, the latter being operated by float controlled means or any other adequate arrangement, so that as the liquid level changes, the rod will be moved longitudinally of itself. Due however to the fact that the operating arm must swing on an arc, equal quantities withdrawn from a cylindrical tank will not produce a uniform movement of the register arm. For instance, when a given amount of liquid is being withdrawn from the upper and lower portions of the cylindrical tank, a rapid fall will be caused in the level of the liquid, but when the float is suspended in the middle portion of the tank, its downward movement will be smaller than when a similar amount of liquid is removed. It is the object of my invention however to provide novel connecting means between the operating rod and the arm which is of such nature that when the rod is moved by withdrawal of equal quantities of liquid from the cylindrical tank rectilinear movement of the rod will produce uniform movement of the arm, and the arm will be swung through an equal portion of the arc of a circle for each unit of measure.

With the foregoing in view, the invention resides in the novel subject matter herein-after described and claimed, the description being supplemented by the accompanying drawings.

Figure 1 is a vertical transverse section of a register showing the operating means in elevation.

Figure 2 is a sectional view at right angles to Figure 1, partly in elevation, showing more particularly the connection between the swinging arm and the operating rod.

In the drawings above briefly described, the numeral 1 designates an appropriate casing within which is mounted a fixed dial 2, an adjustable dial 3, a rotatable dial 4, a pointer 5 cooperable with the dials 2 and 3, a carrying shaft 6 for the pointer 5 and a train of gearing 7 including a gear ring 8 for driving the rotatable dial 4 from the shaft 6. This general subject matter forms no part of the present invention but is merely disclosed to illustrate the application of the improved operating means, and for details of this arrangement, references may be made to the prior patent above referred to.

Mounted loosely on one end of the shaft 6 and positioned within the casing 1, is an operating arm 9 having a dog 10 cooperable with one of the train of gears 7 for rotating the latter when the arm is moved in one direction. This arm is provided with a longitudinal slot 11 receiving the laterally turned end 12 of an operating rod or the like 13 which may well be operated by float mechanism as disclosed in the parent case. The end 12 also extends through a slightly curved slot 14 formed either directly in the back wall 15 of the casing 1, or in a plate 16 secured to said back wall. By reference to Figure 2, it will be seen that as the ends of the slot 14 curve away from the shaft 6, the rod end 12 will be rather remote from the shaft when the arm 9 is either raised or lowered, but will gradually be moved toward said shaft during half the travel of said arm, and gradually moved away from said shaft during the remainder of travel. Thus, uniform rectilinear movement of the rod 13 towards and away from the shaft 6 will cause the arm 9 to swing through an equal portion of the arc of a circle each time a given mount of liquid is removed from the cylindrical tank and this is essential to proper operation of the register.

Since excellent results may be obtained from the details disclosed, they may well be followed, but within the scope of the invention as claimed, numerous minor changes may be made.

I claim:—

1. A mechanical movement comprising a

rock shaft provided with a lateral operating arm having a longitudinal slot, a fixed plate in a plane parallel to that in which said arm swings, said plate having a curved slot, and an operating member having a portion received in the slots of said plate and arm, for the purpose set forth.

2. In an indicator of the character described, actuating means including a rotatable shaft, a lever carried by and extending laterally from said shaft and having a longitudinally extending slot, an actuating rod movable longitudinally of itself in a plane parallel to the plane in which said lever swings and having one end portion fitting into the slot of the lever for movement longitudinally of the lever, and means engaging said rod to move the rod longitudinally of the lever towards and away from

said shaft when the rod is moving longitudinally of itself. 20

3. In a register of the character described, an operating means including a rotatable shaft, a lever carried by the shaft and extending laterally thereof, an actuating rod 25 slidable longitudinally of itself and extending transversely of the lever in a plane substantially parallel to the plane in which said lever swings, said rod being connected with said lever for sliding movement longitudinally of the lever towards and away from the shaft, and means for guiding and controlling movement of the rod towards and away from the shaft when the rod is moving longitudinally of itself. 30

In testimony whereof I have hereunto affixed my signature.

WILLIAM M. TULLEY.
